UNITED STATES PATENT OFFICE.

PAUL H. ZIMMER, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,266,897.

Specification of Letter's Patent.

Patented May 21, 1918.

Application filed April 8, 1918. Serial No. 89,809.

To all whom it may concern:

Be it known that I, PAUL H. ZIMMER, a citizen of the United States, residing at Milwaukee, in the county of Milwaukee and State of Wisconsin, have invented new and useful Improvements in Circuit-Controllers, of which the following is a full, clear, concise, and exact description, reference being had to the accompanying drawing, forming 10 a part of this specification.

This invention relates to circuit controllers particularly adapted for starting alternating current motors, although not limited to such use.

15 In starting certain alternating current motors it is desired to connect the same directly to the supply circuit initially and to thereafter include in circuit fuses for protection thereof during running, and this invention 20 has among its objects to provide a simple, reliable and conveniently operable controller for this and other purposes.

The more specific objects and advantages of the invention will hereinafter appear.

25 The accompanying drawing illustrates one embodiment of the invention which will now be described, it being understood that the controller illustrated is susceptible of various modifications falling within the 30 scope of the appended claims.

In the drawing,

Figure 1 is a front elevation of the controller;

Fig. 2 is a side elevation of Fig. 1, looking to the left;

Figs. 3 and 4 are sectional views taken on line $x-x$ Fig. 1 showing parts of the controller in different positions;

Fig. 5 is a side elevation of Fig. 1, looking to the right;

Fig. 6 is a perspective detail view of parts of the controller; and

Fig. 7 is a diagrammatic view showing the controller employed as a starter for an 45 alternating current motor.

Referring to Figs. 1 and 7 of the drawing the controller includes contact arms 1, 2 and 3 to respectively coöperate with stationary contacts 1^a, 2^a and 3^a to connect motor M 50 directly to a three wire supply circuit L, L', L" and to coöperate respectively with stationary contacts 1^b, 2^b and 3^b to insert fuses 4, 5 and 6 between the motor and the supply

lines. As shown in Fig. 1 all of the switch parts and fuses are mounted upon a suitable panel 7 which is provided with insulating barriers 8 and 9 between adjacent fuses and contacts and with two sets of terminals 12 and 13, the former for line connections and the latter for motor connections.

The contact arms 1, 2 and 3 are yieldingly mounted upon an insulating block 14, each of said arms, as best illustrated in Fig. 3, having a pivotal bearing 15 on a metal insert 16 in said block 14 and a spring pressure device 17. As will be observed the pressure devices, which are of conventional form, serve to secure the arms in their respective bearings and to yieldingly hold the same in a close relation with block 14. Block 14 in turn is secured by means of screws 18 (Fig. 1) to a member 19 (Fig. 6) connected by pins 20 and 21 (Figs. 4 and 6) to parallel links 22 and 23 respectively for support and actuation by said links. The link 22 is fixed to a rock shaft 24 journaled in bearings 25 and 26 (Fig. 1) provided on panel 7, while link 23 is connected by a pin 27 (Figs. 4 and 6) to a frame 28 also mounted upon rock shaft 24 but loosely mounted thereon. Thus it will be observed that provision is made for a compound movement of the block 14, and hence for the contact arms, namely an oscillatory movement with the rock shaft 24 as its axis and a substantially reciprocatory movement by oscillation of the parallel links 22 and 23, and as will appear, both of such movements are obtainable by oscillation of rock shaft 24. The rock shaft is provided with an operating lever 30 and with the return spring 31 (Fig. 6) coiled about the same in two sections with its connecting strand bearing upon link 22 and its ends bearing against a cross bar 32 disposed in front of panel 7. Thus the spring 31 biases the rock shaft in a clockwise direction (Figs. 3 and 4) to move the parts into the relation shown in Fig. 3, said parts being stopped in such relation by abutment of a shoulder 33 on frame 28 with the cross bar 32 and by abutment of link 23 with a stop surface 34 on frame 28. Also, a spring 35 is interposed between frame 28 and the panel 7, which spring tends to assist the spring 31 and further tends to oppose movement of frame 28 toward panel 7. Frame 28, however, as

shown in Fig. 6, straddles the link 22 and upon upward movement of said link to the position shown in Fig. 4, the latter abuts the overlying surface 36 of said frame to effect positive movement thereof against the opposing pressure of spring 35 upon continued upward movement of said link.

Thus the operation of the device will be as follows: With the parts in the relation shown in Fig. 3 initial rotation of the shaft 24 against the action of spring 31 will rock only the link 22 with the result of effecting substantial rectilinear movement of the block 14 and contact arms to the position shown in Fig. 4. In such a relation of the parts the link 22, as above noted, engages frame 28 and hence upon continued movement the frame and link mechanism will rock with the shaft to move the contact arms into engagement with the upper contacts 1^a, 2^a and 3^a and compress springs 17 to insure firm engagement of the contacts. Thereupon restraint of frame 28 and release of shaft 24 will effect a return rectilinear movement on block 14 to draw the contact arms downwardly into engagement with contacts 1^b, 2^b and 3^b as shown in Fig. 5.

The locking means for the member 28 comprises an electromagnet 40 mounted upon the panel 7 and provided with a hooked armature 41 to engage a pin 42 projecting laterally from an arm 43 of frame 28, as shown in Figs. 1, 5 and 6. The magnet 40, as shown in Fig. 7, is adapted to be connected across one phase of the motor circuit upon initial closure of circuit whereby its energization is insured by the time the frame 28 reaches the position wherein it is to be locked. This magnet being connected across a phase of the motor circuit will serve to release the contact arms upon failure of voltage or upon blowout of a fuse and the contact arms may be released at will by a pull upon the operating lever 30.

Thus it will be observed that the desired starting and running connections may be established by a uni-directional movement of the operating lever followed by the release of said lever when the member 28 is latched by the magnet. Moreover it will be observed that the controller is at all times biased to off position by both springs 31 and 35 whereby it will be impossible to leave the controller in a dangerous position and that the mechanism inherently requires and insures the establishment of starting connections prior to establishment of running connections.

What I claim as new and desire to secure by Letters Patent is:

1. In a motor controller, in combination, a plurality of coöperating contacts and operating means therefor providing for engagement of one of said contacts with other of said contacts successively for starting and

running connections, said means including a member movable from an extreme position to another extreme position for starting connections and back to an intermediate position for running connections.

70

2. In a motor controller, in combination, a plurality of coöperating contacts, operating means therefor providing for engagement of one of said contacts with other of said contacts successively for starting and running connections said means including a member movable from an extreme position to another extreme position for starting connections and back to an intermediate position for running connections and electromagnetic means associated with said operating means to retain said contacts in running relation.

75

3. In a circuit controller, in combination, a plurality of stationary contacts, a co-operating contact member, supporting means for the latter providing for movement of the same into engagement with said stationary contacts progressively but necessitating movement of said member from initial position to its extreme limit of movement for initial engagement with said contacts and means associated with said supporting means to effect return of said member to initial position directly from any contact engaging position in which said member is left unrestrained.

80

4. In a circuit controller, in combination, a plurality of stationary contacts, a co-operating contact member, supporting means for the latter providing for movement of the same into engagement with said stationary contacts progressively and further providing for return of said member to initial position directly from final position and means associated with said supporting means providing for automatic movement of said member from one of said contacts to another upon restraint of a part of said supporting means and release of another part thereof.

95

5. In a circuit controller, in combination, a plurality of stationary contacts, a co-operating contact member, supporting means for the latter providing for movement of the same into engagement with said stationary contacts progressively and further providing for return of said member to initial position directly from final position, means associated with said supporting means providing for automatic movement of said member from one of said contacts to another upon restraint of a part of said supporting means and release of another part thereof, and electromagnetic restraining means for said former part of said supporting means.

100

6. In a circuit controller, in combination, a plurality of stationary contacts, a movable contact member biased to disengage said stationary contacts and movable to engage the same progressively, means to restrain said member in engaging relation with respect

110

115

120

125

130

to said contacts while permitting movement of the former relative to the latter, and means to automatically move said member from one contact to another when so restrained, said member upon failure of said restraining means being freed to directly return to initial position from any contact engaging position occupied thereby.

7. In a circuit controller, in combination, 10 a plurality of stationary contacts, a coöperating contact member and supporting means for said member providing for movement thereof from initial position to clear one of said contacts and engage another of the 15 same and for return movement of said member to engage the former contact.

8. In a circuit controller, in combination, 20 a plurality of stationary contacts, a coöperating contact member, supporting means for said member providing for movement thereof from initial position to clear one of said contacts and to engage another of the same and for return movement of said member into engagement with the former contact, 25 said member being biased to disengage all of said contacts, means associated with said supporting means to releasably hold said member in engaging relation to said contacts and means associated with said 30 supporting means to effect automatically said return movement of said member for contact engagement but only upon the functioning of said holding means.

9. In a circuit controller, in combination, 35 a plurality of stationary contacts, a coöperating contact member and supporting means for said member providing a compound rectilinear and pivotal movement therefor for engagement thereof with one 40 of said contacts and a return rectilinear movement for engagement thereof with another of said contacts.

10. In a circuit controller, in combination, 45 a plurality of stationary contacts, a coöperating contact member and supporting means for said member providing for progressive rectilinear and pivotal movements thereof for engagement with one of said contacts, return rectilinear movement for engagement 50 with another of said contacts and return pivotal movement for disengagement of the latter contact and restoration of said member to initial position.

11. In a circuit controller, in combination, 55 a plurality of stationary contacts, a coöperating contact member, supporting means for said member providing for pivotal and rectilinear movement thereof, means asso-

ciated with said supporting means to necessitate rectilinear and pivotal movements of 60 said member progressively for engagement with one of said contacts, and means to restrain a part of said supporting means for return rectilinear movement of said member to engage another of said contacts, said 65 member being biased for said return rectilinear movement.

12. In a circuit controller, in combination, 70 a plurality of stationary contacts, a coöperating contact member, supporting means for said member providing for pivotal and rectilinear movement thereof, means associated with said supporting means to necessitate rectilinear and pivotal movements of 75 said member progressively for engagement with one of said contacts, and means to restrain a part of said supporting means for return rectilinear movement of said member to engage another of said contacts, said 80 member being biased for said return rectilinear movement, and also biased for return pivotal movement for direct disengagement of both said contacts.

13. In a circuit controller for alternating current motors, in combination, a movable 85 contact member, a set of contacts to be engaged thereby in an extreme position thereof, for establishment of starting connections, a set of contacts to be engaged by said member in a position thereof intermediate of its initial position and the aforesaid position for establishment of running connections, and supporting means for said member providing for its clearance of said running contacts during its movement from 90 initial position to starting position.

14. In a circuit controller for alternating current motors, in combination, a movable contact member, a set of contacts to be engaged thereby in an extreme position thereof, for establishment of starting connections, a set of contacts to be engaged by said member in a position thereof intermediate of its initial position and the aforesaid position for establishment of running connections, 100 and supporting means for said member providing for its clearance of said running contacts during its movement from initial position to starting position, said supporting means having means associated therewith 105 to provide for automatic movement of said member from starting position to running position.

In witness whereof, I have hereunto subscribed my name.

PAUL H. ZIMMER.
